IRONING MACHINE WITH RECIPROCATING
IRONING SHOEBernard J. Hank, Chicago, Ill., assignor to Con-
lon-Moore Corporation, Cicero, Ill., a corpora-
tion of Delaware

Application September 16, 1948, Serial No. 49,553

18 Claims. (Cl. 38—47)

1

This invention relates to ironing machines, and has to do with ironing machines intended more particularly for domestic use.

In ironing articles by hand, it is customary to move the iron over the articles with a swinging or arcuate movement, first in one direction and then another, such directions being in general substantially perpendicular to one another. This has the effect of smoothing out the articles and preventing wrinkles or creases therein. Further, the changes in direction of movement of the iron, in contact with the article, subjects the threads to substantially the same pressure and tension both lengthwise and transversely of the article, avoiding any distortions thereof and imparting thereto a desirable smoothness and sheen. Hand ironing thus produces a noticeably better finish of the articles than it is possible to accomplish by machine ironing, as usually practiced, but is open to the objection that it involves more time and labor than ironing by machine.

There is disclosed, in Patent No. 2,217,522, issued October 8, 1949, to Frederick K. Mueller, an ironing machine in which the shoe is reciprocated lengthwise of the cooperating roll, this machine, in operation, approximating, in general, hand ironing and imparting to the articles greater smoothness and sheen than is produced by ironing machines in which the shoe is not reciprocated. In the machine of the Mueller patent the ironing shoe is carried by a reciprocatory and rockably mounted shoe operating shaft, this shaft, and with it the shoe supporting arm and the shoe, being reciprocated, in the operation of the machine. When the shoe is in cooperating relation to the roll, it is subjected to substantial pressure which reacts on the shoe operating shaft and tends to bend or spring that shaft to a certain extent. That results in the bearings supporting the reciprocating shaft being subjected to objectionable pressure which tends to cause excessive wear of the parts. My invention is directed to simple and efficient means for reciprocating the shoe supporting arm and with it the shoe, while avoiding subjecting the bearings of the shoe operating shaft to objectionable wear. More particularly, I provide means whereby the shoe supporting arm and the shoe may be reciprocated without reciprocating the shoe operating shaft. To that end, I provide means whereby the shoe supporting arm and the shoe are mounted on the shoe operating shaft for movement thereby to and from the roll and are also mounted for reciprocation lengthwise of the roll relative to the shoe operating shaft, such mount-

2

ing means including means for reciprocating the shoe supporting arm and the shoe. Further, the shoe reciprocating means comprises means whereby the shoe is reciprocated both lengthwise and transversely of the co-operating roll, in one form of my invention, whereby the action of the shoe on the articles being ironed closely approaches the action of a hand operated iron, thereby producing upon the articles that smoothness and sheen which is characteristic of articles ironed by hand. Further objects and advantages of my invention will appear from the detailed description.

In the drawings:

15 Figure 1 is a rear view, partly broken away, of an ironing machine embodying my invention, showing the shoe at the limit of its movement in one direction lengthwise of the roll;

20 Figure 2 is a fragmentary sectional view, on an enlarged scale, taken substantially on line 2—2 of Figure 1, certain parts being shown in elevation and broken away;

25 Figure 3 is a fragmentary detailed view, on an enlarged scale, taken from the rear, of the shoe operating shaft and the shoe supporting and operating arms thereon, and associated parts, certain parts being broken away and certain other parts being partly broken away and shown in section;

30 Figure 4 is a sectional view taken substantially on line 4—4 of Figure 3;

Figure 5 is a sectional view taken substantially on line 5—5 of Figure 3;

35 Figure 6 is a view similar to Figure 1 but showing a modified form of my invention;

Figure 7 is a fragmentary sectional view, taken substantially on line 7—7 of Figure 6, on an enlarged scale, certain parts being shown in elevation and certain other parts being broken away and shown in section;

40 Figure 8 is a sectional view, on an enlarged scale, taken substantially on line 8—8 of Figure 7, certain parts being shown in elevation and certain other parts being shown partly in elevation and partly in section;

45 Figure 9 is a fragmentary horizontal sectional view of the gear housing and associated parts taken substantially on line 9—9 of Figure 7, certain parts being shown partly in plan and partly in section;

50 Figure 10 is a fragmentary rear elevational view, on an enlarged scale, of the machine of Figure 6, showing the shoe supporting arm operating shaft, the shoe supporting arm, the means

55 ating shaft, the shoe supporting arm, the means

for oscillating the latter arm, and associated parts;

Figure 11 is a sectional view taken substantially on line 11—11 of Figure 10, certain parts being shown in plan;

Figure 12 is a sectional view taken substantially on line 12—12 of Figure 10;

Figure 13 is a front view of the coupling head and associated parts for coupling the shoe supporting arm to the shoe operating arm fixed on the rockably mounted shoe operating shaft;

Figure 14 is a front view of the shoe operating arm;

Figure 15 is a fragmentary horizontal sectional view of the shoe and the mounting bracket therefor and associated parts, on an enlarged scale, the upper end of the shoe supporting arm and the ball connecting member carried thereby being shown in plan, and the roll being shown fragmentarily and in plan, this figure showing a second modified form of my invention;

Figure 16 is a sectional view taken substantially on line 16—16 of Figure 15, certain parts being shown in elevation and the shoe being shown partly in end view and partly in section; and

Figure 17 is a diagrammatic rear elevational view of the shoe and the roll, illustrating the reciprocation of the shoe lengthwise of the roll and transversely thereof in the modified form of my invention shown in Figures 15 and 16.

I have illustrated my invention, by way of example, as embodied in an ironing machine which is, in general, similar to that disclosed in the above identified Mueller patent and to that disclosed in Patent No. 2,054,631, issued Sept. 15, 1936, to Rudolph W. Janda for ironing machine.

The machine comprises a suitable stand 20 having a top bed plate 21 supported by depending legs 22. A main gear housing 23, closed at its outer end by a removable cover plate 24, is appropriately mounted upon bed plate 21, at one end thereof and extends downward therethrough and upward therefrom. A sleeve 25 is formed integrally with, and extends upward from, bottom wall 26 of housing 23.

A worm gear housing 27, appropriately secured to and depending from gear housing 23, is provided with a collar 28 aligned with a depending bearing boss 29, the latter receiving the lower end portion of a shaft section 30, which passes upward through sleeve 25. A worm wheel 31 is secured upon shaft 30 and meshes with a worm 32 fixed on a shaft 33 rotatably mounted in housing 27, the latter shaft being driven, through a flexible coupling 34, by an electric motor 35 suspended from bed plate 21 by hanger brackets 36.

Shaft section 30 passes upward through a bushing 37 mounted in sleeve 25 with its lower end contacting the upper end of hub 38 of worm wheel 31. Bushing 37 extends above sleeve 25, through an eccentric and clutch assembly designated generally by the reference number 39. The assembly 39 is similar to the eccentric and clutch assembly disclosed in the above identified patent to Rudolph W. Janda and in Patent No. 1,867,839, issued July 19, 1932, to Rudolph W. Janda, and need no be illustrated nor described here in detail, a brief description thereof being sufficient.

The assembly 39 comprises a member 40, loose on bushing 37, having a depending eccentric 41, seating at its lower end upon the upper end of sleeve 25. Suitable means is provided for clutching and declutching member 40 to and from shaft section 30. This clutch means is controlled by a trip finger 42 pivoted to the front wall 43.

of gear housing 23 and normally held in operative position. Finger 42 is connected, by a rod 44, to an arm 45 secured upon a pin 46 rockably mounted through a lug 47, extending inward from the upper portion 43a of front wall 43 of gear housing 23. An angle lever 48 has its lower end secured upon pin 46, extends through a slot 49 in wall portion 43a, and is provided at its outer end with a head or knob 50. The lever 48 normally is held in its outer position by a coil wire spring 51 disposed about pin 46, with one arm engaged beneath arm 45 and its other arm extending across the top of lug 47, in front of lever 48 and effective as a stop for limiting outward movement thereof. Spring 51 also serves normally to hold trip finger 42 in normal position, effective for declutching member 40 from shaft section 30 and maintaining it declutched.

When lever 48 is moved inward a short distance, trip finger 42 is moved into inoperative position, releasing the clutch means, which is spring-actuated, thus clutching member 40 to shaft section 30 for rotation therewith. Lever 48 is moved inward but momentarily, and is then released, returning finger 42 to operative position. Rotation of member 40 with shaft section 30 continues during a pre-determined portion, about 180°, of the ensuing rotation of shaft section 30, at which time an element of the clutch contacts finger 42 and member 40 is declutched from shaft section 30. In this manner member 40 is clutched to shaft section 30, turns therewith to a pre-determined extent, and is then automatically declutched therefrom. The particular clutch means employed is not of the essence of my invention, though I preferably employ the clutch means disclosed in Patent No. 1,867,839, above referred to. Suffice it to state that suitable means is provided for optionally clutching member 40 to shaft section 30 for rotation therewith to a predetermined extent, and declutching member 40 from the shaft section 30 when it has been turned to the desired extent.

Shaft section 30 is disposed below and coaxially with an upper shaft section 52 rotatably mounted through a relatively thick rib 53 (Figures 2 and 8) extending from the inner end wall of gear housing 23. Shaft section 52 is provided, at its lower end, with a reduced squared stud 54 which fits into a corresponding bore in the upper end of an elongated hub 55 of an eccentric 56 conveniently formed integral with hub 55, or otherwise fixed thereto. The lower shaft section 30 is provided, at its upper end, with a reduced squared stud 57 which fits into a corresponding bore in the lower end of hub 55. In this manner, the two shaft sections 30 and 52 are coupled together for rotation as a unit.

An ironing roll 58 (Figures 1 and 2), provided with a suitable pad, extends from gear housing 23 inward over bed plate 21 and parallel therewith. Roll 58 is mounted for rotation about its axis, and is secured to a shaft 59, extending into gear housing 23, and appropriately mounted for rotation. Conveniently, the roll 58 and shaft 59 are mounted and secured together in the manner disclosed in the two above identified Patents No. 1,867,839 and No. 2,054,631. The particular manner of mounting roll 58 and shaft 59, and connecting them together, is not of the essence of my invention, and need not be set forth in greater detail. Suffice it to state that the roll and the shaft are rotatably mounted and connected together in an appropriate manner.

The roll shaft 59 is driven, as desired, from

shaft section 52 through a change speed gearing assembly indicated generally by the reference number 60. The assembly 60 is similar to that disclosed in Patent No. 2,054,631, and need not be described here in detail. It has associated therewith suitable control means whereby shaft 59, and consequently roll 58, may be driven at either one of two speeds, or rotation of the roll may be prevented, as desired. The control means is operated by control rod 61 mounted for turning movement through a boss 62 at the bottom of upper portion 43a of front wall 43 of gear housing 23. The rod 61 also extends through and projects outward beyond a plate 63, seated upon the outer face of boss 62, suitably secured thereto and extending downward therefrom to the upper surface of bed plate 21. An operating handle 64 is secured upon the outer end of rod 61, the inner end of which is connected, by a universal connection 65, to the forward end of a turnably mounted control member 66. Means is also provided, comprising a two part control lever 67 and a cooperating eccentric 68 rotatable with member 40, for automatically enabling and disabling the drive between assembly 39 and the roll shaft 59, in accordance with predetermined turning of the latter. The variable speed driving means and associated controls referred to, are fully disclosed in Patent No. 2,054,631, and need not be described in greater detail here. If desired, any other suitable means may be provided for driving the roll shaft, such, for example, as the means disclosed in Patent No. 1,867,839 or in Patent No. 2,026,345, issued Dec. 31, 1935, to Rudolph W. Janda, for ironing machine. It will be seen from what has been said, that the shaft sections 30 and 52, together with hub 55 of eccentric 56, as shown in Figure 8, constitute a unit or shaft and that this shaft has appropriate driving connection to the roll for driving or rotating the latter from the motor 35. It should be noted here that the mechanism shown in Figure 8 is that shown in the form of the ironing machine of my invention disclosed in Figures 6 to 14, inclusive, of the drawings, and differs slightly from the corresponding mechanism in the form of the machine of my invention shown in Figures 1 to 5, inclusive, as will be explained more fully later. In both forms, the connection between the shafts 30 and 52 is essentially the same, there being some differences in detail due to the manner in which the shoe supporting arm and the shoe carried thereby are, in each case, reciprocated. The ironing machine illustrated and so far described, is, in general, similar to that disclosed in Patent No. 2,054,631.

The gear housing 23 is provided, at its inner rear corner, with an exterior tubular boss 70. A tubular shaft 71 is suitably mounted for rotation in boss 70, at its outer portion, and extends therefrom along bed plate 21 in proximity thereto and parallel with roll 58, and is rotatably mounted at its inner end portion in a bracket 72 bolted to bed plate 21. The shaft 71 extends outward through boss 70 into the gear housing 23, for a purpose which will appear more fully presently. A shoe operating shaft 73 is suitably mounted for rotation in shaft 71 and projects a substantial distance inward therebeyond, shaft 73 also projecting beyond the outer end of shaft 71 into the gear housing 23.

A shoe operating arm 74, shown more clearly in Figures 3 and 5, is feathered on the inner end portion of shaft 73, by means of keys or splines 75 fitting in corresponding recesses in collar 76

at the lower end of arm 75 and engaging in diametrically opposite lengthwise grooves or keyways 77 in shaft 73. The shoe operating arm 74 is straddled by the bifurcated lower end of the shoe supporting arm 78 mounted for turning movement on shaft 73 and contacting the ends of collar 76 at the lower end of the shoe operating arm 74. Means, including an emergency release lever 79, is provided for normally coupling the arms 74 and 78 together for movement as a unit. It will be clear, from what has been said, that when the two arms 74 and 78 are coupled together, they may be moved to and from the roll 58 by turning of shaft 73 in alternately opposite directions. Also, the two arms 74 and 78 may be reciprocated lengthwise of shaft 73 by appropriate means, as will be explained more fully presently. An ironing shoe 80, conveniently heated by electrical resistance elements contained therein, is mounted upon the upper end of arm 78 for movement therewith to and from roll 58. This shoe 80 is of known construction and has a concaved ironing or operating surface conforming in transverse curvature and in length to the cooperating surface of the roll 58. It will be clear that the shoe 80 is mounted on shaft 73 and connected thereto for movement thereby to and from the roll 58, when the arms 74 and 78 are coupled together. The means for coupling and uncoupling the arms 74 and 78 is similar to that disclosed in Patent No. 1,867,839. It is not essential to my invention, however, that that particular coupling means be used and any suitable means may be provided for coupling the arms 74 and 78 together, and for disconnecting or uncoupling them.

An arm 82 (Figure 2) is secured upon the outer end of the shoe operating shaft 73, within gear housing 23, and extends downward therefrom. The lower end of arm 82 is connected, by a universal connection 83, to the rearward end of a connecting rod 84, provided at its forward end with an eccentric strap 85 fitting about eccentric 41. Turning of eccentric 41 to predetermined extent, into one position turns shaft 73 about its axis in one direction, and turning of the eccentric from that position through 180° into its other position, turns shaft 73 about its axis in the other direction. In that manner, the eccentric 41 serves to turn shoe operating shaft 73 about its axis in alternately opposite directions and to predetermined extent, effective for moving the shoe 80 to the roll 58 in cooperating relation therewith and moving the shoe away from the roll out of such cooperating relation.

The shoe 80 is of known construction and comprises face plate 86 and associated heating elements 87 secured to the plate by means of suitably spaced clamp members, the central one of which is shown at 88, bearing on a clamp plate 89, the clamp members 88 being secured in position by screw studs welded to face plate 86 and passing through the clamp members 88, the studs receiving nuts screwed thereon, as is known. In Figure 2 the securing stud and nut have been omitted for clearness of illustration. The central clamp member 88 is provided with a pair of spaced rearwardly extending ears 90 rigidly secured thereto, conveniently formed integral therewith. The ears 90 receive between them the upper end of the shoe-supporting arm 78, on which shoe 80 is pivotally mounted by a pin 92 passing through ears 90 and the upper end of arm 78. The shoe 80 is thus mounted on the arm 78 for movement thereby

to and from roll 58 and for movement with arm 78 lengthwise of roll 58, as will appear more fully presently.

A beveled gear 93 is secured on the outer end of shaft 71, within the gear housing 23, and meshes with a beveled gear 94, fixed on the rearward end of a stub shaft 95, rotatably mounted, in suitable bushings 96, in a boss 97 integral with the upper wall of the lower portion of gear housing 23. A beveled pinion 98 is secured on the forward end of stub shaft 95 and meshes with a beveled gear 99 having an elongated hub 100. The hub 100 of the beveled gear 99 corresponds to the hub 55 of the eccentric 56 of Figure 8, and establishes driving connections between the shafts 30 and 52 in the same manner as hub 55 of eccentric 56. It will be clear, from what has been said, that when the machine is in operation the tubular shaft 71 is rotated.

Referring to Figures 1 and 3, the shaft 71 projects inward a substantial distance beyond bracket 72 and receives the elongated hub 101 of a cam disc 102, hub 101 being secured to shaft 71 in a suitable manner, as by means of a set screw 103. The disc 102 is provided with two cam elements or lobes 104 which are disposed at opposite faces of disc 102, are oppositely directed and are spaced 180° apart. The cam lobes or elements 104 cooperate with an inverted U-shaped bracket 105 fixed to the shoe supporting arm 78, conveniently integral therewith at the outer side thereof. During rotation of the shaft 71, the cam element 104 at the outer face of disc 105 contacts the outer arm of bracket 105 and moves the shoe supporting arm 78 toward the left, as viewed in Figure 3. As the cam element 104 at the outer face of disc 102 passes out of contact with the outer arm of bracket 105, cam element 104 at the inner face of disc 102 enters the bracket 105 in contact with the inner arm thereof, and shifts the shoe supporting arm 78 toward the right. In that manner, the shoe supporting arm 78 and with it the shoe operating arm 74, is reciprocated lengthwise of shaft 73 when the machine is in operation, and the shoe 80 is reciprocated lengthwise of roll 58 in contact with the articles being ironed. The reciprocation of the shoe 78 and associated parts is permitted by the splines or keys 75 slideable in the keyways 77 of shaft 73, it being noted that the reciprocation of arm 78 is a rectilinear reciprocation. The collar 101 of cam disc 102 abuts the inner side of bracket 72 and in cooperation therewith restrains the tubular shaft 71 against lengthwise movement outward. A collar 106 is secured on the shaft 73 in a suitable manner, as by means of the set screw 107, and abuts a washer 108 seating on the inner end of shaft 71, serving in cooperation with shaft 71 to restrain shaft 73 against relative outward movement lengthwise. Lengthwise movement of the shafts 71 and 73 inward is prevented by the beveled gear or pinion 93 secured on shaft 71 and the arm 82 secured on shaft 73, appropriately arranged relative to each other and to the adjacent portion of the gear housing 23, as will be understood.

It will be clear, from what has been said, that in the operation of the machine the shoe 80 may be moved to and from the roll 58 as desired and is reciprocated lengthwise of the roll, as indicated by the arrows in Figure 1, in contact with the articles being ironed. That is desirable as imparting to the articles a finish and

sheen approximating that produced by hand ironing, as above explained. It will also be noted that reciprocation of the shoe supporting arm 78 and the parts carried thereby is effected without reciprocation of either the shaft 73 or the shaft 71, which is desirable for the reasons previously explained.

In the modified form of my invention shown in Figures 6 to 14, inclusive, a sleeve 110 is secured at its outer end portion in boss 70 and extends therefrom inward over the top plate or cloth pan 21 of the machine, the inner end of this sleeve being secured in a bracket 111, bolted to the top plate 21. If desired, a sleeve similar to sleeve 110 may be provided about the shaft 71 of the machine shown in Figures 1 to 5, inclusive, as will be readily understood. A tubular shoe operating shaft 112 is rockably mounted in sleeve 110 and projects beyond the inner and the outer ends thereof. Arm 82 is fixed on the outer end of shaft 112 for turning it to predetermined extent in alternately opposite directions, as above described. Arm 82 abuts the outer end of sleeve 110 and restrains shaft 112 against inward lengthwise movement. A stop collar 113 is fixed on shaft 112 and abuts the inner side of bracket 111 (Figures 10 and 11) and, in cooperation therewith, restrains shaft 112 against lengthwise outward movement.

A mounting bracket 114, of substantially U-shape in plan, is mounted for turning movement on the inner end portion of shaft 112 in abutting relation to the inner face of collar 113. The bracket 114 straddles collar 115a at the lower end of a shoe operating arm 116 fixed on shaft 112, this collar 115a fitting snugly between the arms of member 114. A shoe supporting arm 115 is pivoted at its lower end, by a shouldered cap screw 118, on the bight element 119 of bracket 114. The shoe supporting arm 115 extends upward from bracket 114 and has pivoted thereon coupling means comprising a member 120. The coupling means is similar to the coupling means of the Janda Patent 1,867,839 and need not be described in detail. It comprises a rod 121 adjustable through member 120 and having secured on its inner or forward end an arcuate coupling head 122. The shoe operating arm 116 is provided, at its upper end, with an arcuate coupling head 123 provided with an upwardly opening slot 124 of substantial length for reception of the rod 121. When the shoe supporting arm 115 is coupled to the shoe operating arm 116, the head 122 is disposed in front of head 123 of arm 116 (Figures 12 to 14, inclusive), with rod 121 extending through the slot 124. Preferably, head 123 of arm 116 is provided with anti-friction bearing balls 125, extending beyond its inner or forward face, for contact with the outer or rearward face of head 122, for reducing friction and permitting swinging movement of head 122 relative to head 123, as will appear more fully presently. As will be understood from what has been said, when the two arms 115 and 116 are coupled together, the shoe supporting arm 115 may be moved to and from the roll 58 by rocking of shaft 112 in proper direction. When the arm 115 is uncoupled from the arm 116, it may be swung rearward away from the roll 58 about shaft 112, such rearward movement of arm 115 being limited by a stop element 126 on bracket 111, suitably disposed to that end. While I preferably employ the coupling means of the Janda Patent 1,867,839, any suitable means may be provided for coupling together and uncoupling the arms 115

and 116, within the broader aspects of my invention.

Referring more particularly to Figures 9 and 10 and 11, a shaft 128 is slidably mounted through shaft 112 and projects beyond the inner and the outer ends thereof. At its outer end portion the shaft 128 is provided with a circumferential groove 129 which receives a fork 130 at the rearward end of an arm 131 pivoted on a stud 132 secured in a boss 133 integral with the top wall of the lower portion of gear housing 123. The arm 131 is provided with a forwardly extending fork 134 which straddles the eccentric 56 and extends snugly thereabout. It will be seen that when the machine is in operation the arm 131 is oscillated about stud 132 and the shaft 128 is reciprocated lengthwise through the tubular shaft 112.

Shaft 128 projects inward a substantial distance beyond the bracket member 114 (Figures 10 and 11) and is slidably, at its inner end portion, through a bracket 136 bolted to top plate 21. The bracket 136 has mounted therein splines or keys 137 extending into lengthwise keyways 138 in shaft 128. The splines 137 restrain shaft 128 against turning movement while permitting lengthwise reciprocation thereof in the manner above described.

An arm 140, of approximately L-shape, is fixed at its lower end on shaft 128, between bracket 136 and member 114. Arm 140 is provided, at its upper end, with a rearwardly extending finger 141 which projects through a vertical slot 142, of considerable length, formed in a member 144 projecting from the inner side of the shoe supporting arm 115. That provides pin and slot connection between shaft 128 and the shoe supporting arm 115, effective for reciprocating or oscillating arm 115 about a pivot axis, provided at the lower end thereof by the cap screw 118, when the shaft 128 is reciprocated in the manner above described. Such swinging or oscillatory movement of arm 115 relative to the shoe operating arm 116 is permitted by the arcuate heads 122 and 123 of the coupling means, above described, these heads being, of course, of appropriate extent and concentric, or substantially so, with the axis about which the arm 115 oscillates.

The shoe supporting arm 115 is provided, at its upper end, with the head 146 having a vertical slot 147 therein. This slot 147 receives a pin 148 passing through spacer ears 149 appropriately secured to the shoe 80 in the manner previously described. The lower end of the slot 147 is inclined downward and outward from its center toward each end at 150. When the shoe 80 has been moved to the roll 58 in cooperating relation thereto, and the shaft 128 is reciprocated, shoe 80 is reciprocated lengthwise of the roll in contact with the article being ironed. The inner faces of the ears 149 are rounded, as shown in Figure 10, to accommodate the swinging or oscillatory movement of arm 115, which, at the end of its swinging movement in either direction, is inclined relative to shoe 80 lengthwise thereof. The finger 141 of arm 140 is of such length that it extends through slot 142 when arm 115 is in its rearmost position, limited by the stop element 126 of the bracket 111. It will be understood, from what has been said, that the shoe may be moved away from roll 58 by turning of shaft 110 in proper direction, and that by uncoupling arm 115 from the arm 116 the shoe may be swung into its rearmost position in contact with the stop element 126.

The modified form of the machine of my invention shown in Figures 15 to 17, inclusive, is similar to that of the machine shown in Figures 6 to 14, inclusive, except as to the mounting of the shoe on the shoe supporting arm. Referring to Figure 16, the channel clamp member 88a is provided with a rearwardly extending lug or ear 152 fixed thereto, conveniently formed integral therewith. An angle bracket 153, comprising a rearwardly extending lug or ear 154, is bolted to clamp member 88a in spaced relation to the ear 152. The opposed faces of the ears 152 and 154 are provided with semispherical recesses which receive a spherical ball 155 from which extend, at opposite sides thereof, mounting pins 156. These pins 156 extend through collars 157 at the forked upper end of shoe supporting arm 115a. One of the pins 156, is suitably secured, as by a dog appointed set screw 158, in one of the collars 157. The shoe supporting arm 115a is pivoted at its lower end and is oscillated, in the same manner as the arm 115 of Figure 10, in the operation of the machine. When the shoe 80 has been moved to the roll 58, in cooperating relation thereto, as shown in Figure 16, the swinging or oscillation of the arm 115a reciprocates shoe 80 lengthwise of roll 58 and also reciprocates shoe 80 transversely of the roll.

Referring to Figure 17, when the arm 115a is oscillated about the axis *a* of the cap screw 118, the upper end of arm 115a moves through the arc *b*—*c*. When the arm 115a is in vertical position, shown in full lines, the center *d* of the ball 155 is at the center of the arc of movement of the upper end of arm 115a, that is, the arc of movement of point *d* of ball 155. When arm 115a is swung toward the left into its extreme position in that direction, the point *d* is then at the position *d*—1, and when arm 115a is swung into its extreme position in the other direction toward the right, the point *d* is at the position of *d*—2. It will be seen that in the oscillatory movement of arm 115a, the point *d* rises and falls as it is moved from one extreme position to its other extreme. Since the shoe 80 is in close contact with the article passing between the shoe and the roll, oscillatory movement of the arm 115a causes shoe 80 to move upward and downward, about roll 58, so that the shoe is reciprocated both lengthwise of the roll and transversely thereof. The action of the shoe on the article being ironed thus closely simulates the action of hand ironing and imparts to the ironed articles increased smoothness and sheen over articles ironed in a machine in which the shoe is reciprocated lengthwise only of the roll. In that respect, the machine of my invention shown in Figures 15 to 17 is superior to the other forms of ironing machine embodying my invention disclosed here, while possessing in other respects all of the advantages of those machines.

As above indicated, it will be understood that changes in detail may be resorted to without departing from the field and scope of my invention, and I intend to include all such variations, as fall within the scope of the appended claims, in this application in which the preferred forms only of my invention have been disclosed.

I claim:

1. In an ironing machine, a rotatably mounted roll, a rockably mounted shoe operating shaft, a motor means for driving said roll and rocking said shaft by said motor, a shoe supporting

11

arm movable by said shaft to and from said roll in response to rocking of said shaft and mounted for reciprocating movement relative to said shaft lengthwise of said roll, a shoe mounted on said arm and cooperating with said roll and movable to and from the latter by said arm and reciprocable with said arm lengthwise of said roll, and means actuated by said motor for reciprocating said arm during rotation of said roll.

2. In an ironing machine, a rotatably mounted roll, a rockably mounted shoe operating shaft, a motor, means for driving said roll and rocking said shaft by said motor, a shoe supporting arm movable by said shaft to and from said roll in response to rocking of said shaft and mounted for rectilinear reciprocating movement relative to said shaft lengthwise of said roll, a shoe mounted on said arm and cooperating with said roll and movable to and from the latter by said arm and reciprocable with said arm lengthwise of said roll, and means actuated by said motor for reciprocating said arm.

3. In an ironing machine, a rotatably mounted roll, a rockably mounted shoe operating shaft, a motor, means for driving said roll and rocking said shaft by said motor, a shoe supporting arm carried by said shaft movable thereby to and from said roll in response to rocking of said shaft and mounted for reciprocating movement relative to said shaft lengthwise of said roll, a shoe carried by said arms movable therewith to and from said roll and lengthwise of the latter, and means actuated by said motor for reciprocating said arm during rotation of said roll.

4. In an ironing machine, a rotatably mounted roll, a rockably mounted shoe operating shaft substantially parallel with said roll, a motor, means for driving said roll and rocking said shaft by said motor, a shoe supporting arm carried by said shaft connected thereto by means comprising a key and a keyway extending lengthwise of said shaft whereby said arm has relative reciprocating movement lengthwise of said shaft and is movable by the latter to and from said roll responsive to rocking of said shaft, a shoe carried by said arm movable therewith to and from said roll and lengthwise of the latter, and means actuated by said motor for reciprocating said arm.

5. In an ironing machine, a rotatably mounted roll, a rockably mounted shoe operating shaft substantially parallel with said roll, a motor, means for driving said roll and rocking said shaft by said motor, a shoe supporting arm carried by said shaft connected thereto by means comprising a key and a keyway extending lengthwise of said shaft whereby said arm has relative reciprocating movement lengthwise of said shaft and is movable by the latter to and from said roll responsive to rocking of said shaft, a shoe carried by said arm movable therewith to and from said roll and lengthwise of the latter, a rotatably mounted shaft concentric with said shoe operating shaft, connections between said second shaft and said arm for reciprocating the latter when said second shaft is rotated, and means actuated by said motor for rotating said second shaft.

6. In an ironing machine, a rotatably mounted roll, a rockably mounted shoe operating shaft substantially parallel with said roll, a motor, means for driving said roll and rocking said shaft by said motor, a shoe supporting arm car-

12

ried by said shaft connected thereto by means comprising a key and a keyway extending lengthwise of said shaft whereby said arm is mounted for relative reciprocating movement lengthwise of said shaft and is movable by the latter to and from said roll responsive to rocking of said shaft, a shoe carried by said arm movable therewith to and from said roll and lengthwise of the latter, a rotatably mounted shaft concentric with said shoe operating shaft, means comprising cooperating cam members carried by said second shaft and said arm for reciprocating the latter when said second shaft is rotated, and means actuated by said motor for rotating said second shaft.

7. In an ironing machine, a support with a gear housing at one end thereof, a rotatably mounted roll extending from said housing inward over said support, a rockably mounted shoe operating shaft substantially parallel with said roll extending from said housing inward over said support, a motor, means for driving said roll and rocking said shaft by said motor, a rotatably mounted tubular shaft exterior of and concentric with said shoe operating shaft extending from said housing inward over said support and terminating short of the inner end of said shoe operating shaft, a shoe supporting arm carried by said shoe operating shaft and disposed inward beyond said tubular shaft and connected to said shoe operating shaft by means comprising a key and a keyway extending lengthwise of the latter shaft whereby said arm is mounted for relative reciprocating movement lengthwise of said shoe operating shaft and is movable thereby to and from said roll responsive to rocking of said shoe operating shaft, a shoe carried by said arm movable therewith to and from said roll and lengthwise of the latter, means comprising cooperating cam members carried by said tubular shaft and said arm for reciprocating the latter when said tubular shaft is rotated, and means actuated by said motor for rotating said tubular shaft.

8. In an ironing machine, a rotatably mounted roll, a rockably mounted shoe operating shaft, a motor, means for driving said roll and rocking said shaft by said motor, a shoe supporting arm carried by said shaft movable thereby to and from said roll responsive to rocking of said shaft and mounted for reciprocating movement relative to said shaft lengthwise of said roll, a second shaft concentric with said shoe operating shaft movable relative thereto and having operating connection to said arm effective for reciprocating the latter, a shoe carried by said arm movable therewith to and from said roll and lengthwise of the latter, and means actuated by said motor effective for operating said second shaft for reciprocating said arm.

9. In an ironing machine according to claim 1, a roll and a cooperating shoe, and means for moving said shoe to and from said roll and for reciprocating said shoe relative to said roll both lengthwise and circumferentially of the latter when said shoe has been moved to said roll in cooperating relation therewith.

10. In an ironing machine, according to claim 1, a rotatably mounted roll, a rockably mounted shoe operating shaft, a motor, means for driving said roll and rocking said shaft by said motor, a shoe supporting arm movable by said shaft to and from said roll responsive to rocking of said shaft and mounted for reciprocating movement relative to said shaft lengthwise of said roll, a shoe cooperating with said roll movable to and from the latter by said arm, connections between

said arm and said shoe effective for reciprocating the latter both lengthwise and circumferentially of said roll incident to reciprocation of said arm when said shoe has been moved to said roll in cooperating relation therewith, and means for reciprocating said arm.

11. In an ironing machine according to claim 1, a rotatably mounted roll, a rockably mounted shoe operating shaft, a motor, means for driving said roll and rocking said shaft by said motor, a shoe supporting arm movable by said shaft to and from said roll responsive to rocking of said shaft, said arm being pivoted adjacent one end for oscillatory movement about an axis extending transversely of said shaft and said roll and extending from said axis toward said roll, a shoe cooperating with said roll mounted on said arm adjacent the other end thereof by means comprising a universal connection therebetween whereby when said shoe has been moved to said roll and said arm is oscillated about said pivot axis said shoe is reciprocated relative to said roll both lengthwise and circumferentially of the latter, and means for oscillating said arm about said pivot axis.

12. In an ironing machine according to claim 1, a rotatably mounted roll, a rockably mounted shoe operating shaft, a motor, means for driving said roll and rocking said shaft by said motor, a shoe supporting arm mounted at its lower end on said shaft for movement thereby to and from said roll responsive to rocking of said shaft and for oscillatory movement about an axis extending transversely of said shaft and said roll, a shoe cooperating with said roll mounted on said arm adjacent the upper end thereof by means comprising a universal connection therebetween whereby when said shoe has been moved to said roll and said arm is oscillated about said pivot axis said shoe is reciprocated relative to said roll both lengthwise and circumferentially of the latter, and means for oscillating said arm about said pivot axis.

13. In an ironing machine, according to claim 1, a rotatably mounted roll, a rockably mounted shoe operating shaft, a motor, means for driving said roll and rocking said shaft by said motor, a member mounted on said shaft for movement therewith, a shoe supporting arm pivoted adjacent its lower end on said member for movement thereby to and from said roll responsive to rocking of said shaft and for relative oscillatory movement about a pivot axis extending transversely of said shaft and said roll, a shoe cooperating with said roll mounted on said arm adjacent the upper end thereof by means comprising a universal connection therebetween whereby when said shoe has been moved to said roll and said arm is oscillated about said pivot axis, said shoe is reciprocated relative to said roll both lengthwise and circumferentially of the latter, and means for oscillating said arm about said pivot axis.

14. In an ironing machine according to claim 1, a rotatably mounted roll, a rockably mounted shoe operating shaft, a motor, means for driving said roll and rocking said shaft by said motor, a member mounted on said shaft for movement therewith, a shoe supporting arm pivoted adjacent its lower end on said member for movement thereby to and from said roll responsive to rocking of said shaft and for relative oscillatory movement about an axis extending transversely of said shaft and said roll, a shoe cooperating with said roll mounted on said arm adjacent

the upper end thereof by means comprising a ball and socket connection therebetween whereby when said shoe has been moved to said roll and said arm is oscillated about said pivot axis, said shoe is reciprocated relative to said roll both lengthwise and circumferentially of the latter, and means actuated by said motor for oscillating said arm about said pivot axis.

15. In an ironing machine according to claim 1, a rotatably mounted roll, a rockably mounted shoe operating shaft, a motor, means for driving said roll and rocking said shaft by said motor, a member mounted on said shaft for movement therewith, a shoe supporting arm pivoted adjacent its lower end on said member for movement thereby to and from said roll responsive to rocking of said shaft and for relative oscillatory movement about an axis extending transversely of said shaft and said roll, a shoe cooperating with said roll mounted on said arm adjacent the upper end thereof by means comprising a ball and socket connection therebetween whereby when said shoe has been moved to said roll and said arm is oscillated about said pivot axis said shoe is reciprocated relative to said roll both lengthwise and circumferentially of the latter, a second shaft concentric with said shoe operating shaft having relative lengthwise reciprocating movement, operating connections between said second shaft and said arm for oscillating the latter responsive to reciprocation of said second shaft, and means actuated by said motor for reciprocating said second shaft.

16. In an ironing machine according to claim 1, a rotatably mounted roll, a rockably mounted tubular shoe operating shaft, a motor, means for driving said roll and rocking said shaft by said motor, a member mounted on said shaft for movement therewith, a shoe supporting arm pivoted adjacent its lower end on said member for movement thereby to and from said roll responsive to rocking of said shaft and for relative oscillatory movement about an axis extending transversely of said shaft and said roll, a shoe cooperating with said roll mounted on said arm adjacent the upper end thereof by means comprising a ball and socket connection therebetween whereby when said shoe has been moved to said roll and said arm is oscillated about said pivot axis said shoe is reciprocated relative to said roll both lengthwise and circumferentially of the latter, a second shaft slidably mounted in said shoe operating shaft for relative lengthwise reciprocating movement, means comprising pin and slot connections between said second shaft and said arm for oscillating the latter responsive to reciprocation of said second shaft, and means actuated by said motor for reciprocating said second shaft.

17. In an ironing machine according to claim 1, a rotatably mounted roll, a rockably mounted shoe operating shaft, a motor, means for driving said roll and rocking said shaft by said motor, a shoe supporting arm movable by said shaft to and from said roll responsive to rocking of said shaft, said arm being pivoted adjacent one end for oscillatory movement about an axis extending transversely of said shaft and said roll and extending from said axis toward said roll, the other end of said arm having a lengthwise slot therein, spaced mounting members on said shoe at opposite sides of the slotted end of said arm and having rounded inner faces, a pin extending through said slot and secured in said ears, said pin and ears providing a universal connection be-

tween said arm and shoe whereby when said shoe has been moved to said roll and said arm is oscillated about said pivot axis said shoe is reciprocated relative to said roll both lengthwise and circumferentially of the latter, and means for oscillating said arm about said pivot axis.

18. In an ironing machine according to claim 1, a rotatably mounted roll, a rockably mounted shoe operating shaft, a motor, means for driving said roll and rocking said shaft by said motor, a shoe supporting arm movable by said shaft to and from said roll responsive to rocking of said shaft, said arm being pivoted adjacent one end for oscillatory movement about an axis extending transversely of said shaft and said roll and extending from said axis toward said roll, the other end of said arm having a lengthwise slot therein, the lower end of said slot being inclined from its center outward and downward to the sides of said arm, spaced mounting members on said shoe at opposite sides of the slotted end of said arm and having rounded inner faces, a pin

10
5

extending through said slot and secured in said ears, said pin and ears providing a universal connection between said arm and shoe whereby when said shoe has been moved to said roll and said arm is oscillated about said pivot axis said shoe is reciprocated relative to said roll both lengthwise and circumferentially of the latter, and means for oscillating said arm about said pivot axis.
